UNITED STATES PATENT OFFICE

JOHN N. NELSON, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

OPHTHALMIC MOUNTING

Application filed November 23, 1927. Serial No. 235,273.

This invention relates to an improved construction of ophthalmic mounting; and has for its object to provide such a mounting with a pair of eyewires having their upper edges 5 extending longitudinally in a line substantially parallel with the medial line to the eyewires and having downwardly-inclined inner edge portions, the eyewires being connected together by a bridge bar having downwardly extending inclined side arms conforming with and secured to the correspondingly inclined portions of the eyewires to reinforce these inner portions of the eyewires and provide a mounting of attractive appearance.

The invention further consists in positioning the bridge bar in substantial alignment with the upper horizontal edges of the eyewires.

20 A further object of the invention is the provision of side arms on the bridge member inclined to register with the inclined portions of the eyewires and to extend downward substantially to the medial line thru eyewires 25 to further reinforce and stiffen the inner portions of the eyewires and provide an extended soldering surface for attachment of the bridge thereto.

With these and other objects in view, the 30 invention consists of certain novel features of construction, as will be more fully described, and particularly pointed out in the appended claims.

In the accompanying drawings:

35 Fig. 1 is a front view of my improved ophthalmic mounting showing the arms of the bridge as extending down substantially to the medial line thru the eyewires.

Fig. 2 is an edge view of the mounting 40 showing the arms of the bridge as secured to the inclined portions of the eyewires.

Fig. 3 is the same as Fig. 1 with the exception that the side arms of the bridge extend down to a point a substantial distance 45 above the medial line of the eyewires.

Fig. 4 is a section thru the eyewires on line 4—4 of Fig. 1.

Fig. 5 is a section on line 5—5 of Fig. 1 thru the bridge.

50 It is found in the practical construction

of ophthalmic mountings of precious metal having small metal eyewires, of advantage to have the inner edge portions extend downwardly on an incline from the upper edge of the wire and to provide a bridge bar having side arms inclined inwardly and downwardly to fit the inclined portions of the eyewires and provide an extended attaching surface for connecting the bridge arms to the eyewires, the side arms also serving to reinforce the inner or adjacent portions of the eyewires where strength is most required; and the following is a detailed description of the present embodiment of my invention and showing one construction of mounting by which these advantageous results may be accomplished:

With reference to the drawings, 10 designates the eyewires which are preferably formed circular as at 11 on their lower portions, the upper portions 12 of these eyewires being arranged to extend in a line substantially parallel with the medial line thru the eyewires and have downwardly inclined inner edge portions 13 extending from the parallel portion 12 down to a point adjacent to the medial line thru said eyewires.

These eyewires are connected together by a bridge bar 14 having downwardly and inwardly inclined side arms 15 arranged to extend along the inclined surface of the eyewires and be soldered thereto. In some instances, the lower ends of these side arms extend to the lower edge of the inclination 13 of the eyewire, as best illustrated in Fig. 3, 80 while in other instances these side arms may extend beyond the point of inclination of the eyewires down to substantially the medial line thru these eyewires, as best illustrated in Fig. 1, thereby providing an extended soldering surface and at the same time reinforcing the inner edges of the thin eyewires of precious metal where the greatest strain is applied.

The bridge portion 14 is preferably substantially in alignment with the horizontal portions 12 of the eyewires presenting an attractive appearance to the mounting.

By my improved construction I am permitted to form a frame which is very light in

weight, appearance and construction and at the same time by the reinforcing action of the bridge arms the same is rendered very strong and durable.

5 In some instances, I provide noseguards 16 for supporting the frame in position on the face of the wearer and the construction herein illustrated is provided with temple members 17 pivoted to the eyewires 18.

10 My improved construction of ophthalmic mounting is very handsome and attractive in appearance, is strong and durable in construction and is very light in weight.

15 The foregoing description is directed solely towards the construction illustrated, but I desire it to be understood that I reserve the privilege of resorting to all the mechanical changes to which the device is susceptible, the invention being defined and limited only by 20 the terms of the appended claims.

I claim:

1. An ophthalmic mounting having a pair of eyewires with their upper edges extending in a line substantially parallel with the 25 medial line thru the eyewires and having downwardly inclined inner edge portions each forming a sharply defined oblique angle with the upper edge and providing a surface in a single plane, a substantially rigid connecting bridge bar positioned to lie substantially parallel with said upper edge portion of the eyewires and having downwardly and inwardly inclined portions each providing a surface in a single plane and contacting with 30 said plane surface of the inner edge portion for a substantial extent to provide an enlarged soldering surface along the correspondingly inclined portions of the eyewires.

2. An ophthalmic mounting having a pair 40 of eyewires with their upper edges extending in a line substantially parallel with the medial line thru the eyewires and having downwardly converging inner edge portions each forming a sharply defined oblique angle 45 with the upper edge and providing a surface in a single plane, and a substantially rigid connecting bridge bar having downwardly converging side arms each providing a surface in a single plane and contacting with 50 said plane surface of the inner edge portion for a substantial extent to provide an enlarged soldering surface, the lower ends of which extend to a point adjacent the medial line thru the eyewires.

55 3. An ophthalmic mounting having a pair of eyewires with their upper edges extending in a line substantially parallel with the medial line thru the eyewires and having downwardly inclined inner edge portions, a 60 connecting bridge bar positioned to lie substantially parallel with said upper edge portion of the eyewires and having downwardly and inwardly inclined portions following and contacting for a substantial extent with the 65 corresponding downwardly inclined portions,

each forming a sharply defined oblique angle with the upper edge and a second oblique angle with a portion extending at right angles to the upper edge of the eyewires and soldered thereto, the ends of the bridge side arms extending down substantially to the medial line between said eyewires to reinforce the inner edges of the said eyewires.

70 In testimony whereof I affix my signature.

JOHN N. NELSON.
